UNITED STATES PATENT OFFICE.

CLARENCE BIGSBY GUNN, OF COLLINWOOD, OHIO.

SIGNAL APPARATUS.

SPECIFICATION forming part of Letters Patent No. 787,753, dated April 18, 1905.

Application filed December 15, 1904. Serial No. 236,967.

To all whom it may concern:

Be it known that I, CLARENCE BIGSBY GUNN, a citizen of the United States, and a resident of Collinwood, in the county of Cuyahoga and State of Ohio, have invented a new and Improved Signal Apparatus, of which the following is a full, clear, and exact description.

My invention relates to a device for indicating low pressure in a fluid-pressure system—as, for example, an air-brake line for a railway-train—and for giving signals from the cars of the train to the locomotive. Although capable of other uses, these are the principal objects for which my invention is designed.

As air-brake systems are ordinarily constructed there are conditions which take place which permit the loss of the brake-power without the possibility of any information of such change in conditions being conveyed to the engineer, who has complete charge of the stopping of the trains. There are three principal causes of such results—namely, the cut-out cock becoming closed either by the jarring of the train or otherwise, the train-pipe freezing up, and the couplings not being properly made when the different parts of the train are connected. The first two of these sometimes allow a gradual loss of pressure not sufficient to move the triple valve which governs the flow of air from the train-line to the auxiliary and from the auxiliary to the brake-cylinder into such position as to automatically apply the brakes. In the other case the fault is chargeable to the engineer and train crew.

The principal object of the present invention is to provide means for always conveying a signal to the engineer when any of these accidents occur.

Further objects of the invention will be disclosed in the course of the subjoined description.

Reference is to be had to the accompanying drawings, forming a part of this specification, in which similar characters of reference indicate corresponding parts in all the figures.

Figure 1 is a diagrammatic view of a portion of a train, showing the relative positions of the principal parts of one embodiment of the invention. Fig. 2 is a longitudinal sec-

tional view of a detail which comes within the scope of the invention. Fig. 3 shows a system of electrical connections which is employed. Fig. 4 is a side elevation of a portion of the elements shown in Fig. 3; and Fig. 5 is a fragmentary perspective view of the end of a car, showing a form of coupling which may be employed.

The train-line of the air-brake system which I have chosen for the purpose of illustrating my invention and to which the invention is especially applicable is designated in the drawings by the letter *a*. It is to be understood that any kind of a fluid-pressure brake system may be employed in connection with the invention and also that the invention may be used in connection with a fluid-pressure system for other purposes than air-brakes.

Preferably located upon each car, and especially upon the last car, of the train which is provided with the fluid-pressure system is a cylinder *b* in constant communication through a pipe *c* with the train-line *a*. This cylinder is provided with a piston or plunger *d*, having a rod *e* projecting therefrom. An electric circuit *f* is installed upon the train and provided with terminals *g* and *g'*, located in an insulating-frame *h*, preferably connected with the body of the cylinder *b* by a skeleton frame *b'* or the like. The frame *h* is provided with a perforation *h'*, through which the rod *e* can pass into contact with one of the terminals. When the normal pressure is present in the train-line *a*, it will normally force the plunger *d* outwardly, so as to keep the plunger-rod *e* in contact with the terminal *g* and keep the circuit *f* closed. Means is provided for adjusting the plunger *d* so that it may be set to keep the contact closed when any desired pressure is on in the train-line. This means, as shown, comprises an adjustable nut *k* and a spring *l*, bearing upon the nut and upon the rear of the plunger *d*.

It will be readily understood that when any of the accidents above-mentioned take place the gradual decrease of pressure in the train-line will, if the plunger is properly set, permit the plunger to drop back toward the rear of the cylinder, so that the rod *e* will be with-

drawn from contact with the contact-piece g , thus breaking the circuit in the line f . The adjustable parts of the device are preferably so set as to cause this to happen when the 5 pressure is reduced slightly—as, for example, three pounds to five.

The circuit f preferably extends along the whole train, and electrical connection is provided from one car to another by means of a 10 coupling n . (Shown in Figs. 1 and 5.) This coupling is composed in the main of an insulating material, but is provided with a pair of conductors o . The coupling devices are formed in any desired manner, so that when 15 they are forced together they will be caused to securely engage each other and to conduct the currents in the two wires from one car to the other without allowing them to cross.

The conductors f are led to the locomotive 20 through a battery q and through an electromagnet r to a signal device s , which may be in the form of a lamp or in any other desired form. It will be evident that any reduction 25 in the pressure of the train-line below a certain point, which will be fixed by the adjustment of the parts shown in Fig. 2, will be indicated to the engineer by the extinguishing of the light s or by the giving of any signal which any signal device which may be substituted therefor is adapted to give.

In order to provide for giving a signal to the engineer from any of the cars, an additional circuit t is employed. This circuit is provided with signal devices, preferably a 35 light u and a bell u' . This circuit is normally broken and is provided with two terminals v , insulated from each other and from a stationary frame w , in which they are located. The armature r' of the magnet r , which is 40 preferably connected with the cores r^2 of the magnet, is designed to move toward and from the terminals v and to connect them together when in one extreme position. The magnets r are designed to normally pull the armature 45 r' away from the terminals when there is a current in the circuit f . When, however, the circuit f is broken through the means described above or by any other means, the magnets r will become deenergized and the armature r' will drop into contact with the terminals v if the device is located vertically. If it is located horizontally, springs x should be so constructed as to operate to pull the armature into this position. These springs can be 50 used in either case. This connection of the terminals v will obviously operate to set up a current in the circuit t and operate the signal devices u and u' . The battery q can be employed for both circuits, or a separate battery 55 can be employed for each, as desired. I prefer that the light s should be a white light and to have a red light situated at u . This will clearly indicate danger to the engineer when the red light is energized and either with 60 or without the presence of a bell at u' . Push-

buttons can be placed in the cars to break the circuit f and close the circuit t .

It will be readily understood that the invention is capable of embodiment in many other forms than the one illustrated and that many 70 modifications can be made in the form shown without departing from the spirit of the invention.

Having thus described my invention, I claim as new and desire to secure by Letters Patent— 75

1. The combination with a brake system, of an electric circuit, a signal device, means for controlling the electric circuit in response to changes of pressure in the brake system, and means for sending a current through the signal device when said electric circuit is broken. 80

2. The combination of a brake system with an electric circuit, a second circuit which is normally broken, a signal device in the second circuit, means for closing the second circuit 85 from the first-mentioned circuit, and means for opening the first circuit when the pressure in the brake system decreases below a certain point.

3. The combination with a brake system, of 90 an electric circuit, an electromagnet in the circuit having an armature, a second circuit which is normally broken, a signal device in the second circuit, means for closing the second circuit when the magnet is deenergized, 95 and means for opening the first circuit when the pressure in the brake system decreases below a certain point.

4. The combination with a brake system, of 100 an electric circuit, an electromagnet in the circuit having an armature, a second circuit which is normally broken, a signal device in the second circuit, means for closing the second circuit when the magnet is deenergized, 105 and means for opening the first circuit when the pressure in the brake system decreases below a certain point; said first-named means comprising a pair of contact-pieces insulated from each other and each constituting a terminal of the second circuit, said armature constituting an electrical connection between said 110 contact-pieces when the magnet is deenergized.

5. The combination with an electric circuit, and an electromagnet therein having an armature, of a second circuit which is normally open, a signal device in the second circuit, and means for closing said second circuit when the magnet is deenergized. 115

6. The combination with a brake system, of 120 an electric circuit, an electromagnet in the circuit having an armature, a second circuit which is normally broken, a signal device in the second circuit, means for closing the second circuit when the magnet is deenergized, 125 and means for opening the first circuit when the pressure in the brake system decreases below a certain point; said last-named means comprising a cylinder communicating with the 130 brake system, a plunger in the cylinder, and

means connected with the plunger and adapted to keep said first circuit closed when a certain pressure exists in the cylinder.

7. The combination with a conductor containing fluid under pressure, a cylinder connected with said conductor, a plunger in the cylinder, an electric circuit, and means connected with the plunger and adapted to keep the circuit closed when the pressure within the cylinder is above a certain point.

8. The combination with a conductor containing fluid under pressure, a cylinder connected with said conductor, a plunger in the cylinder, an electric circuit, means connected with the plunger and adapted to keep the circuit closed when the pressure within the cylinder is above a certain point, and means for moving the plunger and disengaging said means from the circuit when said pressure decreases below said point.

9. The combination with a conductor containing fluid under pressure, of a cylinder communicating with said conductor, a plunger in the cylinder, a rod connected with the plunger, an adjustable nut connected with the cyl-

inder, a spring located between the nut and the plunger; an insulating-block, and an electric system having terminals within said block, said plunger being adapted to pass into said block and normally hold said terminals in contact with each other when the plunger is forced toward the terminals by the pressure within the cylinder.

10. The combination with a conductor containing fluid under pressure for a railway-train, of a signal device located in the locomotive connected with the train, and means for giving a signal thereon when the pressure in said system decreases below a certain point; said means comprising an electric circuit extending from the rear car to the locomotive, and a coupling for the two conductors of the electric circuit mounted on each car.

In testimony whereof I have signed my name to this specification in the presence of two subscribing witnesses.
